CLAIM

I claim the ornamental design for a fence with solar power cells, as shown and described.

DESCRIPTION

FIG. 1 is a perspective view of a fence with solar power cells of the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view thereof taken along lines 8-8 of FIG. 6.

The broken lines show parts of the fence with solar power cells that represent unclaimed subject matter and form no part of the claimed design.
